(57) **CLAIM**

The original design for a shell for electric connector, as shown and described.

DESCRIPTION

FIG. 1 is a top, front and right side perspective view of the shell for electric connector showing our new design;

FIG. 2 is a right side elevational view thereof;

FIG. 3 is a top plan view thereof;

FIG. 4 is a bottom plan view thereof;

FIG. 5 is a front elevational view thereof; and,

FIG. 6 is a rear elevational view thereof.
